(57) **CLAIM**

The ornamental design for swimming goggles, as shown and described.

DESCRIPTION

FIG. 1 is a top view of the swimming goggle lens design. FIG. 2 is a front view of the swimming goggle lens design. FIG. 3 is a bottom view of the swimming goggle lens design. FIG. 4 is a back view of the swimming goggle lens design. FIG. 5 is a front perspective view of the swimming goggle lens design.

FIG. 6 is a back perspective view of the swimming goggle lens design.

FIG. 7 is a front view of the right-hand-side swimming goggles (to which the opposite lens is symmetrical).

FIG. 8 is a top view of the right-hand-side swimming goggles (to which the opposite lens is symmetrical); and, FIG. 9 is a perspective view of the right-hand-side swimming goggles (to which the opposite lens is symmetrical).

These swimming goggles are characterized by a swept-back appearance with outer tips extended, reminiscent of the masks worn by comic book super heroes.

The broken lines are for illustrative purposes only and forms no part of the claimed design.
